CLAIM

The ornamental design for a deer rails collapsible fence, as shown and described.

DESCRIPTION

FIG. 1 is a right-front perspective view of a deer rails collapsible fence;

FIG. 2 is a right view thereof;

FIG. 3 is a right-rear perspective view thereof;

FIG. 4 is a rear view thereof;

FIG. 5 is a left-rear perspective view thereof;

FIG. 6 is a left view thereof;

FIG. 7 is a left-front perspective view thereof;

FIG. 8 is a front view thereof;

FIG. 9 is a bottom view thereof;

FIG. 10 is a right-front perspective view of the deer rails collapsible fence installed on a base;

FIG. 11 is a right view thereof;

FIG. 12 is a right-rear perspective view thereof;

FIG. 13 is a rear view thereof;

FIG. 14 is a left-rear perspective view thereof;

FIG. 15 is a left view thereof;

FIG. 16 is a left-front perspective view thereof;

FIG. 17 is a front view thereof; and,

FIG. 18 is a bottom view thereof.

The broken lines shown depict portions of the deer rails collapsible fence that form no part of the claimed design.
